UNITED STATES PATENT OFFICE.

FREDERICK G. HUNTER, OF MONCTON, NEW BRUNSWICK.

CARD-HOLDER.

SPECIFICATION forming part of Letters Patent No. 230,016, dated July 13, 1880.

Application filed May 26, 1880. (Model.)

To all whom it may concern:

Be it known that I, FREDERICK G. HUNTER, of Moncton, New Brunswick, have invented a new and Improved Card-Holder, of which the following is a specification.

The object of this invention is to provide a cheap and simple device, especially designed for railroad-cars, to be affixed to the outsides thereof for holding and protecting cards of address, &c.

The invention consists in an improved card-holder constructed substantially as hereinafter described.

Figure 1 represents a front elevation of the device, with a portion broken away, the better to exhibit other parts. Fig. 2 is a cross-section on line x x , Fig. 1.

Similar letters of reference indicate corresponding parts.

In the drawings, A represents a car; B B', the top and bottom plates, respectively, fastened by screws or otherwise upon the said car.

C C are the parallel side rods, having their ends inserted into the sockets a a in the plates B B', and having on their inner faces the toothed flanges b b, the teeth of which serve to hold the card F in place when pressed down on said card by the action of the spring D. This spring D consists of one or more straight rods, whose ends rest on the flanges b b of said side rods, C C, and whose central point or points are held down by the finger E, through which the said rods are passed horizontally, said finger E being attached to the center of the top plate, B.

G G are the thumb-pieces, fixed on the outer

faces of the side rods, C C, near the upper ends thereof. Pressure down upon said thumb-pieces G G turns the side rods, C C, in their sockets, so that the toothed flanges b b are raised that a card may be inserted or withdrawn from beneath them.

H is the sloping cap or cover, secured to the car A immediately above the other parts of the device, to protect it and the cards held by it from rain, &c., said cap H being designed to project forward sufficiently for that purpose.

I is another rod, placed a short distance from the rods C C and parallel therewith, the said rod I being fastened in position on the car A by having its ends bent downward at right angles and driven into said car, and so that sufficient space shall be left between said rod and car to admit of the insertion of a card. This rod I, though a part of the device herein shown and described, is used only when long cards, &c., whose ends require further support, are placed in the rack.

Having thus described my invention, I claim as new and desire to secure by Letters Patent—

As an improved article of manufacture, a card-rack, constructed substantially as herein shown and described, consisting of socketed plates B B', flanged and toothed side rods, C C, provided with thumb-pieces G G, spring D, held by finger E, and cap H, as set forth.

FREDERICK GEORGE HUNTER.
